[75] Inventor: **David Thorne**, Tarzana, Calif.

Primary Examiner—Wallace R. Burke

Assistant Examiner—B. J. Bullock

Attorney, Agent, or Firm—Albert M. Herzog; Edward C. Walsh

[**] Term: **14 Years**

[57] **CLAIM**

The ornamental design for a combined tennis racket holder and shelf, substantially as shown and described.

DESCRIPTION

FIG. 1 is a reduced isometric view of a combined tennis racket holder and shelf, showing my new design;

FIG. 2 is a front elevational view thereof;

FIG. 3 is a top plan view thereof;

FIG. 4 is a side elevational view thereof;

FIG. 5 is a further isometric view thereof;

FIG. 6 is a rear elevational view thereof;

FIG. 7 is a sectional view taken on line 7—7 of FIG. 6.
